WINDOW SEAT

Application filed May 31, 1930. Serial No. 458,578.

This invention relates to a window seat adapted to be easily attached to and detached from a window sill and casing so as to provide a convenient device for washing the outside sides of windows.

The device is constructed so that it may be used with window casings having an inner and an outer sill, and with casings having sills of different dimensions. The device also has an adjustable clamp at its rear end which fits over and clamps it to ledges of window casings which have different thicknesses.

In the accompanying drawings which illustrate the present preferred embodiment of our invention—

Figure 1 is a bottom plan view of the window seat;

Figure 2 is a longitudinal section showing the seat applied to a window casing; and

Figure 3 is an end elevation of the seat as viewed from the right of Figure 2.

Referring more particularly to the accompanying drawings, the window seating device comprises a seat 2 on which one may sit or stand when cleaning the outside of a window. The seat is substantially rectangular in shape and is provided at its rear end with means indicated generally by the reference numeral 3 for clamping the device to a ledge 4 of a window casing 5. Window casings are generally formed with an inner sill 6 and an outer sill 7, the inner sill generally being formed of wood and the outer sill of stone.

The seat 2 is supported on the sills by a support indicated generally by the reference numeral 10, which is adjustable longitudinally of the seat so that the device can be adjusted to fit casings of different widths. The support 10 comprises two blocks 11 disposed on opposite sides of the seat and extending longitudinally thereof, and a transverse connecting member 12. The blocks 11 and the transverse member 12 are secured by screws 13 and slide as a unit longitudinally of the device when it is adjusted to fit a casing of a different width. The transverse member 12 is provided with slots which fit over the blocks 11 and the blocks and member 12 are fastened together by the screws 13.

The position of the seat when attached to a window casing is illustrated in Figure 2. Each of the blocks 11 is recessed to provide an outer step 15 and an inner step 16, which rest on the outer sill 7 and the inner sill 6 respectively. The inner ends 18 of the blocks 11 fit against the vertical offset 19 of the window casing.

The support 10 is guided in its sliding movement by a rear guide 20 and a front guide 21. These guides extend transversely of the seat and are provided at each end with tongues 22 which fit in grooves 23 formed in the blocks 11. The guide 20 is rigidly fastened to the seat 2 by screws 25, but the guide 21 is loosely attached to the seat by bolts 26 and thumb nuts 27. When the thumb nuts 27 are loosened the support 10 may be adjusted longitudinally of the seat, but when the thumb nuts are tightened they clamp the support in adjusted position. Thus the member 21, in addition to acting as a guide for the support 10, also acts in conjunction with the bolts 26 and nuts 27 to clamp the support in adjusted position.

The clamping action of the guide 21 is illustrated in Figure 3. The guide 21 is so dimensioned that the distance from the top surface of the tongue 22 to the top surface 30 of the guide is less than the distance between the top surface of the groove 23 and the bottom surface 31 of the seat 2. With this construction a slight space 33 is normally left between the top surface 30 of the guide 21 and the bottom surface 31 of the seat 2. This space is present when the thumb nuts 27 have been loosened and the support 10 is ready to be adjusted. In this position of the parts the support may be adjusted, the tongues 22 sliding easily in the grooves 23. After the adjustment has been made the wing nuts 27 are tightened, thereby causing a binding of the tongues 22 in the grooves 23 which firmly clamps the support 10 in adjusted position.

The window seating attachment is provided at its rear end with the adjustable clamp 3, by means of which it may be secured to the inner ledge 4 of the window cas-

ing. A strip 40 is secured to the under surface of the rear end of the seat 2 by bolts 41. The bolts 41 project downwardly some distance beyond the strip 40 as viewed in Figure 2 and extend through a strip 42 disposed transversely of the seat. The bolts 41 are disposed adjacent opposite sides of the seat 2 and extend loosely through openings formed in the strip 42. Springs 43 are coiled about the bolts 41 thereby exerting a downward force against the strip 42. The strips 42 are forced toward the seat 2 by turning the thumb nuts 45, thereby bringing the strip 42 into clamping engagement with the ledge 4. The strip 42 and the bottom of the seat 2 are provided with strips 46 of rubber or other cushioning material for preventing the parts from marring the window ledge.

When the thumb nuts 45 are tightened in order to force the strip 42 against the window ledge and so clamp the seat in position, there is a tendency for the front end of the strip 42 to rotate about its longitudinal axis. We overcome this tendency by providing a set screw 47 which is threaded into a metal bushing 48 carried by the strip 42, and which extends through the strip and into contact with a metal washer 49 on the strip 40, the set screw 47 being located to the rear of the line joining the bolts 41. This provides an arrangement by which the seat may be clamped to ledges having different depths and in which rotation of the clamping strip 42 about its longitudinal axis is prevented by the set screw 47.

In attaching the window seat to a window, the seat is placed in position and the set screw 47 is adjusted to correspond to the approximate depth of the ledge 4. The thumb nuts 45 are then turned to give the final adjustment. The support 10 is adjusted relative to the seat so that inner ends 18 of the guide blocks 11 contact with the offset 19 of the window casing. The thumb nuts 27 are then tightened to clamp the support in adjusted position.

The device above described can be easily and cheaply manufactured and provides a rigid support which can be quickly attached to and detached from a window casing.

We have illustrated and described the present preferred embodiment of our invention. It is to be understood, however, that the invention may be otherwise embodied within the scope of the following claims:

What we claim is:

1. A window seating device comprising a seat having at its rear end means for securing it to the ledge of a window casing, a support for the seat adjustable relative thereto for fitting window casings of different widths, a support guide extending transversely of and secured to the under side of the seat, and means for clamping the support to the seat in adjusted position.

2. A window seating device comprising a seat having at its rear end means for securing it to the ledge of a window casing, a support for the seat adjustable relative thereto for fitting window casings of different widths, a plurality of support guides extending transversely of the seat and secured to the under side thereof, one of said support guides having means for clamping the support to the seat in adjusted position. 75

3. A window seating device comprising a seat having at its rear end means for securing it to the ledge of a window casing, a support for the seat adjustable relative thereto for fitting window casings of different widths, a plurality of support guides extending transversely of the seat and secured to the under side thereof, said support and guide being provided with a cooperating tongue and groove, one of the guides being provided with means for clamping the support to the seat in adjusted position. 80

4. A window seating device comprising a seat having at its rear end means for securing it to the ledge of a window casing, a support for the seat adjustable relative thereto for fitting window casings of different widths, said support comprising longitudinally extending supporting blocks disposed at opposite sides of the seat and connected by a transverse connecting member, a plurality of support guides extending transversely of the seat and secured to the under side thereof, said support and guides having tongue and groove sliding engagement, one of the guides having means for clamping the support to the seat in adjusted position. 90

5. A window seating device comprising a seat having at its rear end means for securing it to the ledge of a window casing, a support for the seat adjustable relative thereto for fitting window casings of different widths, said support comprising longitudinally extending supporting blocks disposed at opposite sides of the seat and connected by a transverse connecting member, a plurality of support guides having a tongue at each end and extending transversely of the seat and secured to the under side thereof, each of said supporting blocks being provided at 95

its inner side with a longitudinally extending groove for sliding engagement with tongues on the ends of the guides, one of the guides being loosely secured to the seat, said last named guide being so dimensioned that the distance between the top of the tongue and the top of the guide is less than the distance between the top of the groove and the under surface of the seat, and means for tightening the securing means on said last mentioned guide to clamp the support to the seat in adjusted position. 115

6. A window seating device comprising a seat having at its rear end means for securing it to the ledge of a window casing, said 120

means comprising a strip extending transversely of the seat and adjustable toward and away from the seat to fit window casings having ledges of different depths, means adjacent opposite ends of the strip for tightening it against the ledge, an adjusting screw disposed rearwardly of the line connecting the tightening means, said screw extending through said strip and adapted to contact with a portion of the device to maintain the strip and seat parallel.

5 In testimony whereof we have hereunto set our hands.
